UNITED STATES PATENT OFFICE.

JOSEPH HERGARTEN, OF CHICAGO, ILLINOIS.

LENS-MOUNT.

992,663.

Specification of Letters Patent. Patented May 16, 1911.

Application filed September 26, 1910. Serial No. 583,938.

To all whom it may concern:

Be it known that I, JOSEPH HERGARTEN, a citizen of the United States, residing at Chicago, in the county of Cook and State of Illinois, have invented certain new and useful Improvements in Lens-Mounts, of which the following is a specification.

This invention relates to a simple and improved form of lens mount for eyeglasses and of the type particularly designed to prevent the looseness of the lens when mounted on the nose-piece of the eyeglasses, such looseness being ordinarily incidental to the ordinary screw connection employed for attaching lenses to the frame of the eyeglasses at present commonly used.

The invention resides particularly in the specific construction of the mount employed.

For a full understanding of the present invention, reference is to be had to the following detail description and to the accompanying drawings, in which:

Figure 1 is a front elevation of the invention applied to one form of eyeglass; Fig. 2 is a view of the lens applied to a mount constructed in accordance with the invention looking from the side opposite to that from which Fig. 1 is taken; Fig. 3 is a section taken about on the line 3—3 of Fig. 2; Fig. 4 is a fragmentary view disclosing the detail construction of the present invention. Fig. 5 is a detail perspective view of the pivoted clamp member and Fig. 6 is a different form of eyeglass embodying the invention.

Throughout the following detail description and on the several figures of the drawings similar parts are referred to by like reference characters.

Specifically describing the invention, a lens mount constructed in accordance therewith consists of the usual stud A adapted to be secured to the nose-piece B of the glass, the lenses being indicated at C. Each stud A is formed with the usual arch-shaped cross piece 1 provided with a suitable seat to receive an end of the lens in the customary manner and on the opposite sides of the lens are arranged a movable clamp member 2, and a relatively stationary member 3 both

being connected with the cross piece 1 of the stud A. Preferably the stationary clamp member 3 consists of a flat lug, integral with the side of the cross piece 1, the opposite side of the cross piece being formed with outwardly projecting lugs 4 between which the lugs 5 formed on the clamp member 2 are arranged, a pivot pin 6 passing through the adjacent lugs 4 and 5 so as to pivotally connect the same together. Encircling the pivot member 6 is a coiled spring 7, one end of which is secured to an end of the pivot member and the opposite end of which projects outwardly at 7' against the outer face of the clamp member 2 thereby tending to hold said clamp member in engagement with the side of the lens with which it coöperates. The clamp member 2 is formed with spaced projections 8 adapted to engage in openings formed in the lens C, said projections 8 being so spaced as to bring the points in engagement thereof with the lens in planes above and below the point at which the clamp member 3 engages the lens on the opposite side. The two clamp members, 2 and 3, therefore coöperate with the lenses 75 by engagement on opposite sides and furthermore the clamp member 2 has interlocking connection with the lens at two different points preventing likelihood of looseness of the latter once it has been engaged by the clamp members. The outer end of the clamp member 2 may be curved outwardly to form the finger piece 2', permitting ready grasping of the clamp member to detach the lens 3 after the latter becomes broken, or for the substitution of a new lens.

Having thus described my invention, what is claimed as new is:

As a new article of manufacture, a mount for lenses comprising a stud formed with a cross piece having a seat to receive an end of the lens, said cross piece being provided with an integral rigid clamp member at one side thereof adapted to engage with one side of the lens, and a movable clamp member at the opposite side of the cross piece, matching lugs projecting from the cross piece and said second clamp member, a pivot pin pass-

ing through said lugs and connecting the clamp member to the cross piece, said movable clamp member having projections extending from its inner side to enter openings 5 in a lens, the outer end of the pivoted clamp member being bent outward to form a finger piece, and a spring encircling the pivot pin and having an end thereof projecting out-

wardly into yieldable engagement with the outer side of the pivoted clamp member. 10

In testimony whereof I affix my signature in presence of two witnesses.

JOSEPH HERGARTEN.
